ELECTRIC ARC EXTINGUISHING MEDIUM

William S. Edsall, Belmont, Mass., assignor to
Condit Electrical Manufacturing Corporation,
Hyde Park, Mass., a corporation of Massa-
chusetts

Application October 16, 1931, Serial No. 569,293

4 Claims. (Cl. 200—144)

This invention relates to a novel medium for extinguishing an electric arc such as is formed between the separable contacts of an electric switch or interrupter when it opens under load 5 and when a fuse blows.

One of the main requirements of an arc extinguishing medium is that it should extinguish the arc rapidly so that the circuit positively is known to be interrupted within an instant following the mechanical separation of the separable contacts or current carrying parts of the circuit interrupter, to permit switching operations to be carried out in closely-timed order, and to clear trouble from the circuit as quickly 15 as possible. The rapid extinguishing of the arc is also highly desirable to avoid destruction of the arc-supporting members of the interrupter and the creation of high pressure of the extinguishing medium.

20 Further requirements of the extinguishing medium are that it should be inert with respect to the materials of the switch with which it is in contact, stable under the action of the arc, and with the air so that there is no danger of explosion or fire hazard. The arc extinguishing medium 25 also should be electrically insulating, so that it isolates the separated parts of the circuit, and should be capable of indefinitely repeated use.

Various liquid arc-extinguishing mediums have 30 been proposed of which the one most universally used is oil. Oil, however, is a complex chemical compound, is decomposed by the action of the arc into simpler hydrocarbons, one of which is carbon which can form a dangerous electrically 35 conducting bridge between the interrupter terminals, and others of which are fixed gases which can collect under dangerous pressure in the enclosing casing of the interrupter. The oil and the vapors and gases thereof are combustible in 40 air and have resulted in damaging explosions within the interrupter casings and fires externally thereof.

Other insulating liquids, as carbon tetrachloride, have been used to some extent but in general are volatile at ordinary temperatures, decompose under the action of the arc and react chemically with the parts with which they are 45 in contact.

Electrolytes, as water, have been used to some 50 extent but are conducting so as to require an especial design of the interrupter or the use of additional air or oil break switches in series with the terminals of the interrupter to provide positive assurance of potential isolation of the parts of 55 the mechanically separated circuit.

A gaseous arc extinguishing medium has certain advantages over a liquid medium. A gaseous medium, by reason of its lower density and viscosity, permits more rapid separation of the submerged interrupter contacts than a liquid 5 medium; and the gaseous medium can move more quickly than a liquid into effective relation with the arc. While atmospheric air is commonly employed as the arc extinguishing medium in a certain class of switches, it is unable to extinguish 10 the circuit interrupting arc rapidly and requires a long separation of the contact members of the switch for high voltages. Other gaseous media such as air under elevated pressure and carbon dioxide have been suggested, but without 15 successful results.

I have conducted tests with various gaseous arc extinguishing media especially to determine their ability to rapidly extinguish circuit-interrupting power arcs and have discovered that 20 helium, especially at an elevated pressure, can extinguish electric arcs much more rapidly than any other gas known to me that has been proposed for this purpose. Hence a novel arc extinguishing medium comprising helium con- 25 stitutes an object of the present invention, because of its ability to satisfactorily contribute to or effect the desired rapid extinguishment of the arc.

Fig. 1 illustrates curves showing the relation 30 for various gases, between the number of cycles of alternating current arc duration, or rapidity of arc extinction, and arc current.

Fig. 2 are curves showing the effect of pressure on rapidity of arc extinction. 35

Fig. 3 is a sectional view, more or less diagrammatically shown, of an electric switch adapted for use with the arc extinguishing medium embodying the present invention and, used to obtain the data for the curves of Figs. 1 and 2. 40

The switch herein shown comprises the pressure tight casing 10 having the removable cover 12, which carries the insulating bushings 14 having the exposed terminals 16 and the main current carrying, or brush, members 18 and arc- 45 ing members 20 within the casing. The switch includes a movable switch member having a lifting rod 22 terminated in a bridging member 24 which engages the brush members 18 and carries the current when the switch is closed, and the 50 movable arcing members 26 which engage the stationary arcing members 20 and between them support the circuit interrupting arcs formed as the switch opens under load. The movable arc- 55 ing members are connected both electrically and

mechanically by a conductor 28 that is carried by the lifting rod and has looped portions 30 adjacent the arcing members 26 that provide magnetic blow-out fields in the arc zones and also maintain the pairs of arcing members in engagement prior to the separation thereof. In this respect the arrangement is as described in the Ainsworth Patent No. 1,762,604. The lifting rod is connected with suitable switch operating mechanism, not shown, arranged preferably mainly within the casing in such manner as to minimize possibility of gas leakage. The switch casing contains the gaseous arc extinguishing medium under substantial pressure above the atmosphere.

Fig. 1 is a set of experimentally-obtained curves illustrating the time of duration of alternating-current sixty-cycle arcs, measured in cycles, for various arc currents and for the gases, air, nitrogen and helium. It will be noted that the arc duration in helium is much shorter, for any arc current, than in either air or nitrogen and that, for currents above one thousand amperes, the time of duration of arc current is less than one cycle for helium while it is about five times as great for air and nitrogen. It will also be noted that for higher arc currents, upwards of two thousand amperes, the arc is extinguished in helium in about one-half a cycle, which is as fast as is desired as a more rapid extinction may set up serious surges in certain circuits. On the other hand, for the same arc currents, neither air nor nitrogen approach half cycle extinction.

The pressure of the medium, above a certain value, has no appreciable effect on the time of arc duration. Fig. 2 is a set of curves showing the relation between time of arc duration and pressure, for helium and nitrogen. It will be noted that a pressure variation from sixty to one hundred eighty pounds gage resulted in practically no reduction in the time of arc duration. This is true also of air and other gaseous arc extinguishing media. The figure also illustrates the marked superiority of helium over nitrogen as an arc extinguishing medium.

In addition to its superiority over other media, helium has been found to be inert to the action

of the arc. Air oxidizes the switch contacts. Nitrogen unites with any moisture present to form an acid which attacks the switch parts. Carbon dioxide is decomposed with deleterious results. Hydrogen combines readily with various substances and is combustible with air.

I claim:

1. In the art of rapidly interrupting high-voltage high-power alternating current circuits in which relatively movable solid contact members are disengaged for interrupting the circuit, the method of breaking the circuit which comprises drawing a heavy current arc by disengaging said contact members, and rapidly extinguishing said arc in less than one cycle of arc current by subjecting said arc to an atmosphere of helium at upwards of four atmospheres pressure.

2. In the art of rapidly interrupting high-voltage high-power alternating current circuits carrying upwards of five hundred amperes by disengaging relatively movable solid contact members, the method of interrupting the circuit which comprises drawing an arc by disengaging said solid contact members, and extinguishing the arc in less than one cycle of arc current by subjecting said arc to an atmosphere of helium at upwards of four atmospheres pressure.

3. In the art of rapidly interrupting high-voltage high-power alternating current circuits in which relatively movable solid contact members are disengaged for interrupting the circuit, the method of interrupting the circuit which comprises drawing a power arc by disengaging said contact members, and subjecting said arc to a rapid-arc-extinguishing atmosphere of helium at upwards of four atmospheres.

4. An electric circuit interrupter for high-power high-voltage electric circuits carrying upwards of five hundred amperes, said interrupter comprising relatively movable solid contact members between which an arc is drawn when said members are separated, and means for extinguishing said arc in less than one cycle of arc current comprising an atmosphere of helium at upwards of four atmospheres pressure in which the arc is drawn.
